LAST

Helge Gulbrandsen, Beverly, Mass., assignor to
 United Shoe Machinery Corporation, Flem-
 ington, N. J., a corporation of New Jersey

Application January 24, 1950, Serial No. 140,338

7 Claims. (Cl. 12—123)

1

This invention relates to lasts and particularly to an adjustable last to be placed inside a shoe to withstand pressure applied to the shoe bottom, for example, during cement attachment of a sole to a shoe in repair work.

Such lasts are usually made of metal and do not fill the shoe as does a wooden last but do approximately fit the inner face of the insole, at least forward of the breast line. Since in usual repair work shoes of many different heel heights are presented, it is desirable to provide adjustment between the forepart portion of the last and the shank portion to accommodate shoes having various heel heights since otherwise a large number of different lasts would be required.

Objects of the present invention are to provide a last having a forepart and shank portion relatively movable about an axis extending transversely of the shoe and located substantially at the ball line whereby the last is self-adapting to fit shoes of varying heel heights and to provide means dependent on application of pressure to the last to hold the forepart and shank portions of the last against relative movement.

The illustrated device comprises a rigid body portion which carries a pressure-receiving member, said member being movable relatively to the body portion. Removably secured to the body portion is a plate shaped to substantially cover the upper surface of the forepart of the insole inside the shoe. To the body portion at the ball line a shank plate is pivoted so that when the last is placed in a shoe with the forepart in contact with the insole the shank plate will drop automatically into contact with the shank portion of the insole. A link is pivoted to the shank plate at one end, said link being supported below by the body portion and having its upper surface engaged by a surface formed on the above-mentioned pressure-receiving member. Thus, when pressure is applied to the pressure-receiving member, the link is securely held and movement of the shank plate relatively to the forepart plate is prevented.

If it is desired to increase the locking effect, a portion of the sides of the link, instead of being vertical, may be inclined toward each other in a downward direction, each side being inclined, say at about ten degrees, from the vertical. Corresponding surfaces are provided on the body portion which engage the inclined sides of the link so that downward pressure applied to the link will wedge it between the corresponding surfaces of the body portion and the link will be held securely from movement.

A single shank plate is satisfactory for a wide range of shoe sizes but the forepart plate should be interchangeable with different sized plates

2

to accommodate a run of shoe sizes. The forepart plate is therefore made readily detachable from the body portion so that a proper sized forepart plate for the work in hand may be substituted. Usually three forepart plates of different sizes will be sufficient.

In the drawings—

Fig. 1 is a side view of the last and pressure-applying device, a shoe and resilient pad being shown in section, and

Fig. 2 is a sectional view taken on the line II—II of Fig. 1.

The last of the present invention is intended for use with a resilient pad 10 and a pressure-applying device 12 which may be of any usual construction, the pad 10 supporting the sole of a shoe, and the device 12 being operable to apply downward pressure to the last and force the shoe against the pad with sufficient pressure to effect permanent cement-attachment of the sole to the shoe.

The last comprises a body portion 14 on which is a portion 16 having a flat lower face lying in a recess in the upper side of a forepart plate 18, said plate having the shape of the forepart of the insole of a shoe. The forepart plate 18 is detachably secured to the portion 16 by a screw 20 threaded therein and engaging a forwardly open slot in the portion 16. Plates 18 of several different sizes or shapes may be provided to accommodate a series of shoe sizes and are preferably thick enough at their peripheries to afford support for the shoe upper.

A shank plate 22 is loosely pivoted at 24 to the body portion 14 and has its counterclockwise movement (Fig. 1) limited by engagement of a lug 26 thereon with a lug 28 on the body portion 14, its clockwise movement being sufficient to enable it to accommodate itself to a shoe having a high heel. When the last is out of the shoe the plate 22 will assume, by gravity, a position in which the lug 26 engages the lug 28, the plate 22 being then in substantial alinement with the forepart plate 18, as required by a shoe having no heel. When the last is placed in a shoe with the forepart plate 18 in contact with the forepart of the insole, the shank plate 22 will automatically assume a position against the shank portion of the insole irrespective of the angle that the shank portion of the insole makes with the forepart of the insole, that is, irrespective of the height of the heel.

Pivoted at 30 to the shank plate 22 is a link 32, preferably curved from the pivot 24 as a center, the lower side of which rests on the body portion and the upper side of which lies under a surface 34 on a pressure-receiving member 36 which is pivoted to the body portion at 38. The member 36

has its movement about the pivot 38 limited by a pin 40 seated in the body portion 14 and engaging a notch 42 in the member 36, the notch being large enough to permit the surface 34 to engage the link 32 when the member 36 receives pressure. With this construction, when a last is placed in a shoe upon the pad 10 with its forepart engaging the insole of the shoe, the shank plate 22 will drop into contact with the shank portion of the insole of any shoe, whatever its heel height, and when pressure is applied by the pressure-applying device 12 to the pressure-receiving element 36 its surface 34 will engage the link, force it against the body portion and lock it, and hence the shank plate 22, against movement.

The invention contemplates the provision of cylindrical engaging surfaces on the body portion and link. However, in case a positive locking effect is desired, the arrangement shown may be provided in which the lower edge portion of the link 32 is wedge shaped and engages a correspondingly shaped groove in the body portion. The lower portions of the sides of the link 32 may, for example, be inclined inwardly toward each other at 44 (Fig. 2), each side being at an angle of say ten degrees to the vertical, and corresponding outwardly flaring surfaces may be provided on the body portion 14 so that when pressure is applied to the link its lower tapered portion will be wedged between surfaces on the body portion, and the link 32 positively held from movement under any pressure to which the last is likely to be subjected.

For engaging the pressure-receiving member 36, the pressure-applying device 12 is provided with a foot 46 having a semi-cylindrical flange 48 and a flat face 50 to engage the member 36. The flange 48 is received in a complementary groove 52 formed in the lower end of the device 12 and is held therein solely by a tension spring 54 connected at its upper end to a pin 56 in the device 12 and at the lower end to a pin 58 in the flange 48. The spring 54 is located in bores, respectively, in the device 12 and in the flange 48 which are sufficiently large to permit rocking of the foot 46 about the center of curvature of the flange 48 which lies substantially in the surface 50 of the foot so that the foot can accommodate itself to various inclinations of the pressure-receiving member 36.

Having thus described my invention, what I claim as new and desire to secure by Letters Patent of the United States is:

1. A last for shoe repair work comprising, in combination, a body portion, a forepart plate and a shank plate carried by the body portion and relatively movable about an axis located substantially at the ball line, and a member connected to one of said plates, said member being supported by the body portion and constructed and arranged to receive pressure applied to the last for locking said plates against movement relatively to each other.

2. A last for repair work comprising, in combination, a body portion, a forepart plate fixed to the body portion, a shank plate pivoted to the body portion about an axis located substantially at the ball line of the last, and a member connected to the shank plate, supported by the body portion and arranged to receive pressure applied to the last for holding the shank plate for movement relatively to the forepart plate about said axis.

3. A last comprising, in combination, a body portion, a member movable with respect to the body portion, a forepart plate and a shank plate, both plates being carried by the body portion, said plates being movable relatively to each other about an axis extending transversely thereof at the ball line, and a link connected to one of said plates and lying between the body portion and the movable member whereby application of pressure to said movable member will hold said plates against movement relatively to each other.

4. A last for use in repairing shoes comprising, in combination, a body portion, a forepart plate secured to the body portion, a shank plate pivoted to the body portion, a link curved from said pivot as a center, said link being pivoted to the shank plate, and means responsive to pressure applied to the last for holding said link.

5. A last for use in the cement-attachment of soles to shoes in repair work comprising, in combination, a forepart plate and a shank plate relatively movable about an axis located at the ball line of the last to render the plates self-conformable to the longitudinal contour of the inside of a shoe bottom, a body portion carrying said plates, a member on the body portion, movable with respect thereto, to which pressure is applied, and a link connected to one of said plates and supported by the body portion, said member contacting said link and being adapted when pressure is applied thereto to lock said link and hold the plate attached thereto from movement relatively to the other plate.

6. A last for use in the cement-attachment of soles to shoes comprising, in combination, a forepart plate, a shank plate freely movable relatively to the forepart plate about an axis located at the ball line of the last, the plates being thus conformable to the longitudinal contour of the inside of the shoe bottom, a body portion carrying said plates, a pressure-receiving member on the body portion movable with respect thereto, and a link pivoted at one end to the shank plate and supported by the body portion, said member engaging said link and being adapted when pressure is applied to lock the link and hold the shank plate from movement relatively to the forepart plate.

7. A last for use in the cement-attachment of soles to shoes comprising, in combination, a forepart plate and a shank plate relatively movable about an axis located at the ball line of the last to render the plates self-conformable to the longitudinal contour of the inside of a shoe bottom, a body portion carrying said plates, a movable member on the body portion to which pressure is applied, and a link connected to one of said plates and supported by the body portion, said link and body portion having interengaging wedging surfaces, said movable member engaging said link and acting when pressure is applied thereto to cause interengagement of said surfaces to hold one plate from movement relatively to the other plate.
